UNITED STATES PATENT OFFICE

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN

COOLING UNIT

Application filed January 31, 1930. Serial No. 425,018.

This invention relates to cooling units, and has to do particularly with cooling units of the type adapted to be used for cooling large areas, such as display cases, butcher boxes, etc.

More specifically, the present invention has to do with what might be termed a multiple unit lowside, each unit or section of which is of very simple but efficient construction and the several units of which may be readily joined together to form a complete cooling unit of any desired size. In this case, the multiple units of the lowside take the form of a metal casing, each adapted to interlock with the other and each provided with a conduit and suitable means for positioning the conduits within the casing; said casings serving as molds for the positioning means and the positioning means serving as a hold over for the cooling unit.

In the drawing:

Fig. 1 illustrates a typical installation of my novel cooling unit.

Fig. 2 is a sectional view illustrating the method of assembling the multiple units together.

Fig. 3 is a fragmentary sectional view illustrating one manner of sealing the joints between the multiple units.

In my Patents No. 1,671,761 and No. 1,671,762 I have disclosed the use of stone in forming lowsides for mechanical refrigerating systems, said stone acting as a hold over in place of brine. The present invention has to do with a particular embodiment of this use of stone in combination with a novel form of cooling unit.

The cooling unit of the present invention may be made up of any desired number of units and in Fig. 2 I have shown three of such units as at 1, 2, and 3. Each section preferably consists of an outer piece of copper tubing 4 the diameter of which will depend upon the particular use to which the unit may be subjected.

This length of copper tubing 4 will serve as a mold in forming each complete multiple unit. In completing each unit, a suitable conduit 5 may be positioned within the

50 mold and the mold then filled with stone.

The conduit 5 is preferably positioned so that one end protrudes from the unit as at 6, a suitable core having been placed in the other end of the unit to form the enlarged cavity 7.

The copper tubing used is preferably of standard stock and thus relatively inexpensive. When the multiple units are assembled, the stone filling is hermetically sealed and thus may be of the cheapest grade of oxychloride cement or other artificial stone. The interior pipes 5 may or may not be necessary as it will be obvious that suitable conduits may be formed directly in the stone. In this case, any suitable means may be utilized for forming joints between the respective units.

In assembling the units, the protruding portions 6 of the conduits 5 are preferably coated with suitable sealing material, such as synthetic rosin or any other similar substance and the two adjacent units joined together. After this operation, a suitable sleeve 8 may be moved to the position shown in Fig. 3. This sleeve may be sweat into position or given any suitable operation so as to substantially seal the joint.

It will be obvious that the respective units may be fabricated and assembled at the place of installation and thus all that is necessary is a supply of lengths of copper tubing and corresponding lengths of conduits. These may be cut off as desired at the place of installation, although, of course, it would be preferable to have standard lengths to make up the general construction of the entire lowside. Suitable elbow joints 3 may be provided and these, of course, may be distorted considerably so as to fit into any particular installation.

Regardless of whether the cooling unit is formed at the place of manufacture or at the place of installation, it will be obvious that all that is necessary is to pour the artificial stone into place and immediately join the units together, the final setting of the stone taking place after assembly. This use of the outer copper casing as a mold thus eliminates many hours which would otherwise be required in allowing the stone to

set. Also the combination of copper casing and stone inner wall provides a very strong unit capable of large ice melting capacity and at the same time providing sufficient 5 hold over capacity.

What I claim is:

1. A multiple unit lowside for mechanical refrigerating systems, comprising a plurality of complete independent units directly 10 joined together and contacting end to end to form a continuous conduit for receiving and circulating a refrigerant, each of said units being provided with a permanent wall of solid material surrounding the conduit 15 and formed of a substance which acts as a hold over, said permanent walls being connected together to form a continuous wall of hold over material for said continuous conduit.
2. A multiple unit lowside for mechanical refrigerating systems, comprising a plurality of units joined together end to end to form a continuous conduit for receiving and circulating a refrigerant, each unit consisting 25 of a metallic tube, a conduit, and a lining of stone between the conduit and the wall formed by the metallic tube, said linings of stone in the connected together units forming a continuous stone structure.
3. A multiple unit lowside for mechanical refrigerating systems comprising a series of separate units joined together to form a complete lowside, each separate unit consisting of an outer casing and an inner wall 35 of stone, said casings forming a mold for said stone, said inner wall of stone in the joined together units forming a continuous stone structure.
4. A lowside for mechanical refrigerating 40 systems, comprising a plurality of separate units connected together, each unit being provided with a conduit registering with the next adjacent unit whereby to form a continuous conduit for receiving and circulating 45 a refrigerant, a wall of plastically applied stone surrounding the conduit in each unit and forming a continuous wall of stone in the connected together units and a casing surrounding each wall of stone and adapted 50 to serve as a mold for the stone, when plastically applied.
5. A lowside for mechanical refrigerating 55 systems, comprising a plurality of separate units connected together, each unit being provided with a conduit registering with the next adjacent unit whereby to form a continuous conduit for receiving and circulating 60 a refrigerant, a wall of plastically applied stone surrounding the conduit in each unit and forming a continuous wall of stone in the connected together units and a casing surrounding each wall of stone and adapted 65 to serve as a mold for the stone, when plastically applied, and means for con-

necting adjacent units together whereby to seal the same.

6. A lowside for mechanical refrigerating systems comprising a plurality of cylindrical units, said units consisting of a cylindrical outer casing, internally positioned conduits and an intermediate wall of stone, said units being adapted to be connected together to form a complete lowside of any desired length and shape, and said conduits intermediate wall of stone registering one with the other when said units are joined together to form a continuous stone structure and continuous inner and outer structures.

In testimony whereof I affix my signature. 80
LLOYD G. COPEMAN.
